TO R. J. GRAF, ALL OF SAN FRANCISCO, CALIFORNIA.

INTERMITTENT FILM-FEEDING MECHANISM.

1,227,887.

Specification of Letters Patent. Patented May 29, 1917.

Application filed May 20, 1916. Serial No. 98,882.

To all whom it may concern:

Be it known that we, HERSCHEL M. CONNOR and DON D. MILES, both citizens of the United States, both residing at San Francisco, in the county of San Francisco and State of California, have invented certain new and useful Improvements in Intermittent Film-Feeding Mechanisms; and we do hereby declare the following to be a full, clear, and exact description of the invention, such as will enable others skilled in the art to which it appertains to make and use the same.

This invention relates to film feeding mechanisms and has for its object to provide a device of this character especially useful in taking and projecting moving pictures, and which will be simple in construction, comparatively inexpensive to manufacture, and more efficient in action than those heretofore proposed.

With these and other objects in view, the invention consists in the novel details of construction and combinations of parts more fully hereinafter disclosed and particularly pointed out in the claims.

Referring to the accompanying drawings forming a part of this specification in which like numerals designate like parts in all the views:

Figure 1 is a diagrammatic elevational view partly in section of a film feeding mechanism made in accordance with this invention;

Fig. 2 is an elevational view of the parts shown in Fig. 1 as seen from the left of said figure;

Fig. 3 is a detail sectional view taken on the line 3-3 of Fig. 2 showing the parts about to engage the film preparatory to feeding it in a downward direction;

Fig. 4 is a view similar to Fig. 3 showing the position of the parts after the film has been engaged and it is about to start on its downward movement;

Fig. 5 is a view similar to Fig. 3 but showing the parts after having completed their downward feeding motion;

Fig. 6 is a view similar to Fig. 5 but showing the position of the parts upon disengaging the film;

Fig. 7 is a detail view of the feeding mechanism showing the adjustment of the

parts to accommodate pictures that have been placed in different positions on the film;

Fig. 8 illustrates one position of the pictures on the film; and

Fig. 9 illustrates another position of the pictures on the film;

1 indicates any suitable frame work, 2 any suitable source of power as for example a hand operated crank connected to the power shaft 3, operating the gears 4, 5, 6, 7, and 8, adapted in turn to operate 65 the film feeding sprockets, the moving parts of the shutter as well as the film feeding devices proper. 9 represents a shaft for operating the film feeding sprocket 10, 11 the shaft for operating the film feeding 70 sprocket 12, 13 a bevel gear meshing with the bevel pinion 14 operating the sleeve 15 carrying the revolving portions of the shutter 16, and 17 represents the film passing around the sprocket 10 between the guides 75 18 and 19 to form the loop 20 and passing down between the aperture plate 21 and the curved plate-like film guide 22, all as will be clear from the drawings.

The aperture plate 21 is provided with 80 the slots 24 through which pass the film feeding pins 25 carried by the feeding lever 26 provided with the slot 27 in which slides the block 28. Rigid with the gear 7 is the driving shaft 30 extending through the balance wheel 31, through the pillar block 32, (see Figs. 2 and 7), and carrying beyond said pillar block the circular shoulder 34 integral with the cam 35 provided with the pin 36 mounted in the above mentioned sliding block 28 and adapted to reciprocate the same in the slot 27 as the cam 35 and shaft 30 rotates.

Also mounted on the feeding lever 26 are the roller members 37 and 38 provided with 95 the pins 39 and 40 respectively. As the said cam 35 rotates, it constantly contacts with the roller 37 while the spring 41 secured as at 42 to the frame work constantly bears against the pin 40 and thereby exerts 100 a pressure which maintains at all times the contact with the said roller 37 and the said cam 35. The effect of this arrangement of parts is to move the lever 26 up and down on the pivot 43 and also to cause the same 105 to slide longitudinally of its length on said

pivot which is located in the slot 44, or in other words, to move said lever 26 and the feeding pin 25 in and out of the film 17, all as will be clear from the drawings.

5 The particular function of the spring 41 is to maintain a yielding firm contact with the cam 35 and roller 37 in the above described movements, so that no jarring or rattling will occur during the feeding operation. On the other hand, should the spring 10 41 break, the cam 35 will strike the roller 37 and the roller 38 alternately and still continue to feed the film, although in such case more or less noise will occur.

15 It will be observed that the parts are so arranged that should they be in the position shown in Fig. 3, and should the cam 35 be turning in a counter-clockwise direction, as seen in said figure, the pin 25 will be moved longitudinally of the lever and will be projected through one of the openings 45 in the film 17 and into the substantial position shown in Fig. 4. The crank pin 20 36 will now cause said feeding pin 25 to move downward through the slot 24 in the aperture plate 21 and also through the slot 25 46 in the guide plate 22 until the said pin 25 attains about the position illustrated in Fig. 5.

30 After having passed the said position shown in Fig. 5, the cam 35 continuing to revolve in a counter-clockwise direction will permit the spring 41 to withdraw the pin 25 out of the perforations 45 and the slots 35 46 and 24 so that it will occupy substantially the position shown in Fig. 6. A continued revolution of the cam 35 and crank pin 36 will now raise the said lever 26 around its pivot 43, whereupon the pin 25 40 will be brought back to about the position illustrated in Fig. 3, and the above cycle of operations will be repeated.

After the film 17 is thus fed say in a downward direction, by the movements of 45 the feeding pins 25 it forms a loop and by the continuously rotating sprocket 12 is passed on to the winding up reel, not shown. It is obvious that upon a reversal of the rotation of the crank 2 and the driving shaft 50 30, the said film 17 will be fed upward as seen in Fig. 1, instead of downwardly. It often happens that pictures such as 51 are placed on films such as 17 with their border lines 52 extending between the centers 55 of opposite perforations 45 all as will be clear from Fig. 8. It also often happens that pictures such as 56 are so located that their border lines 53 extend between the centers of the spaces 54 between said perforations 45, as will be clear from film 57.

In other words, pictures are frequently displaced longitudinally of the film by a distance equal to about one half of the space 54 between the driving perforations 45. In 60 such case, since the feeding pins 25 have a

fixed distance of travel up and down, if they are properly set to feed pictures located on a film 17 as is indicated in Fig. 8, said pins 25 would continuously improperly feed pictures such as 56 located on a film 70 such as 57 shown in Fig. 9.

Accordingly, it is desirable to provide means by which a machine such as that made the subject of this application will be enabled to feed films such as 17 or such as 75 57 with indifference or with equal efficiency.

In order to accomplish this desirable purpose, we provide an adjusting means such as the screw threaded member 60 located in the base 61 and having the pin 43 acting as 30 a pivot for the lever 26 and also provided with the adjusting nut 62 by which said pin 43 may be moved up and down, so that the initial or stationary position of the pivot may be located at different distances from 35 the base 61, and so that therefore, the said feeding pins 25 will begin their downward motions at points corresponding to the adjusted positions of the pivots 43.

Stated in still other language, should the 90 pins 25 be properly adjusted for feeding a film such as 17 and should a film such as 57 be threaded into the machine it would only be necessary to raise or lower the pivot 43 by a distance sufficient to change the initial position of the pin 25 through a distance equal to one half the distance of the space 54. After such adjustments have been made then the film 57 will be fed by the pins 25 in such a way as to always bring the centers 100 of the pictures 56 to coincide with the center of the aperture. This is an important feature of the invention, because it enables the operator by the simple turning of the nut 62 to insure a proper feeding of 105 films such as 57 without the necessity of having to change the aperture itself, or the optical axis of the lens.

It will be further observed that the curved slot 46 greatly aids in accomplishing this 110 desirable result, for should a straight slot be employed, and should the feeding pins 25 be made to travel over two different arcs, displaced with reference to each other, in the manner just disclosed, it is evident that 115 the extremity of one arc or the other would be positioned so far away from said straight slot as to render the engagements and disengagements between said pins 25 and said perforations 45 extremely uncertain. No 120 such uncertainty exists when a curved slot 46 is employed, and when the said adjustment is made at right angles to the lever 26, or lengthwise of the slot 46 as disclosed.

In the drawings 65 represents the aperture or optical axis of the lens, 66 the aperture tube, 67 the film gate, 68 the diaphragm or shutter aperture, 69 the shutter plate, 70 a shaft for turning through the gear 5, the bevel gear 13 and shutter 16. 125 130

The operation of the machine will be clear from the foregoing but may be briefly summarized as follows:—

The film 17 being threaded through the camera as indicated in Fig. 1, the crank 2 is turned, and through the train of gears illustrated and by specific connections, not shown, the sprockets 10 and 12 are continuously turned with the crank 2 and the film 10 is continuously fed out around the sprocket 12. The shaft 30 is turned through the pinion 7 and the same being rigid with the cam 35 and crank pin 36, the said cam reciprocates the feeding pin 25 while at the same time the crank pin 36 swings the feeding lever 26 on its pivot 43 so that the said pin 25 starting in the position shown in Fig. 3 successively attains the positions shown in Figs. 4, 5 and 6, whereupon it returns to the 20 position shown in Fig. 3.

In other words, the said feeding pins 25 move in and out of the perforations 45, while at the same time they move up and down, thus intermittently feeding the said 25 film in a downward direction, while the said sprockets 10 and 12 are continuously rotating. If a film such as 57 is substituted for the film 17, whereon the pictures 56 are somewhat displaced, as indicated in Fig. 9, 30 then by adjusting the nut 62 the pivot 43 of the lever 26 is correspondingly adjusted and said feeding pins 25 will feed the film 57 as accurately as the film 17. Stated in other language, pictures such as are displaced on 35 a film as are the pictures 56 shown in Fig. 9, may have their centers accurately brought to coincide with the optical axis of the camera by the simple means of adjusting the nut 62 and thus the trouble and annoyance of 40 having to adjust the aperture and optical axis of the lens is avoided. In addition to the above, the spring 41 maintains a firm and yielding contact between the roller 37 and cam 35 thus also avoiding any impact 45 between said cam and roller, as well as noise and wear. On the other hand, should the spring 41 break, then the cam 35 will force the lever 26 in one direction by contacting 50 with the roller 37 and will positively force it in the opposite direction by contacting with the roller 38, so that the breaking of the spring does not in the least interfere with 55 the operation of the feed.

Another important feature of this invention resides in the fact that this feed is especially adapted for a compact form of camera occupying only relatively a very small space and which is suitable for both professional and amateur use. In such a camera 60 the saving of space is an important item and we are enabled to economize space in this feed by making the plates 21 and 22 curved as at 75 so that the upper portion of the said plates lettered 21 and 22, are thrown 65 farther to the left as seen in Fig. 1, than

otherwise would be the case, which enables us to locate the sprockets 10 and 12 as well as the other moving parts of the camera farther to the left than would otherwise be possible. The result is the said moving parts 70 of the camera occupy a space that is much smaller than it would be possible for them to occupy were the parts 75 in the same straight line with the parts 21 and 22.

It is obvious that those skilled in the 75 art may vary the details of constructions as well as the arrangement of parts without departing from the spirit of the invention and therefore we do not wish to be limited to the above disclosure except as may be required by the claims:—

What we claim is:—

1. In a film feeding mechanism the combination of a curved plate provided with a slot and adapted to guide a film having perforations; a pivoted lever having film feeding means adapted to enter said slot and perforations; means for reciprocating said film feeding means lengthwise of said slot; means for adjusting the pivot of said lever 85 lengthwise of said slot; and means for reciprocating said film feeding means into and out of said slot and perforations, substantially as described.

2. In a film feeding mechanism the combination of a plate having a curved slot and adapted to guide a perforated film; a pivoted lever having film feeding means; means for adjusting the pivot of said lever lengthwise of said slot, a revolving crank adapted 100 to reciprocate said feeding means lengthwise of said slot; and a cam adapted to reciprocate said feeding means transversely of said slot, substantially as described.

3. In a film feeding mechanism the combination of a curved plate provided with a slot and adapted to guide a film having perforations; a pivoted lever having film feeding means adapted to enter said slot and perforations; means for reciprocating said 105 film feeding means lengthwise of said slot; means for reciprocating said film feeding means into and out of said slot and perforations; and means for adjusting the position of the pivot of said lever lengthwise of said 110 slot, substantially as described.

4. In a film feeding mechanism the combination of a plate having a curved slot and adapted to guide a perforated film; a pivoted lever having film feeding means; a revolving crank adapted to reciprocate said feeding means lengthwise of said slot; a cam adapted to reciprocate said feeding means transversely of said slot; and means 120 for adjusting the position of the pivot of said lever lengthwise of said slot, substantially as described.

5. In an intermittent film feed, the combination of a plate having a curved slot, a feeding lever having a pivot and a feeding 125

- point adapted to traverse said slot; a crank pin and sliding block for moving said lever in opposite directions transverse to its length; a cam for moving said lever in opposite directions longitudinally; and means for moving the pivot of said lever lengthwise of said slot to change the transverse path of travel of said point, substantially as described. 40
- 5 10. In an intermittent film feed, the combination of a feeding lever having a pivot and a feeding point; a crank pin and sliding block for moving said lever in opposite directions transverse to its length; a cam and spring for moving said lever in opposite directions longitudinally; and means comprising an adjustable support for moving the pivot of said lever at right angles to its length to change the transverse path of 45
- 15 travel of said point, substantially as described. 50
- 20 15. In a film feed, the combination of a film feeding lever adapted to feed films carrying pictures located in predetermined positions relative to their perforations; and means for changing the position of the pivot of said lever in a direction lengthwise of said films to cause it to feed films having pictures located in other predetermined positions with relation to said perforations, substantially as described. 55
- 25 20. In a film feed, the combination of a lever provided with a reciprocating film feeding point adapted to feed films carrying pictures located in predetermined positions relative to their perforations; and means comprising an adjustable support for 60
- 30 changing the position of the pivot of said lever in a direction lengthwise of said films to cause said point to feed films having pictures located in other predetermined positions with relation to said perforations, substantially as described. 65
- 35 8. In a film feed, the combination of a lever provided with a reciprocating film feeding point adapted to feed films carrying pictures located in predetermined positions relative to their perforations; and means comprising an adjustable support for changing the position of the pivot of said lever in a direction lengthwise of said films to cause said point to feed films having pictures located in other predetermined positions with relation to said perforations, substantially as described. 70
- 40 9. In a film feed the combination of a lever provided with a pair of slots and a film feeding point; a sliding block located in one of said slots; a pivot block over which said lever may slide located in the other slot; a crank pin connected to said first named block; a roller carried by said lever; a cam associated with said crank pin adapted to contact with said roller; and means for adjusting the position of said second named block and pivot, substantially as described. 45
- 45 10. In a film feed the combination of a slotted guide plate; a lever provided with a pair of slots and a film feeding point; a sliding block located in one of said slots; a pivot block over which said lever may slide located in the other slot; a crank pin connected to said first named block, adapted to reciprocate said point longitudinally of its corresponding slot; a roller carried by said lever; a cam associated with said crank pin adapted to contact with said roller to move said point transversely of said last named slot; and means for adjusting the position of said second named block and pivot to enable said point to feed films having pictures relatively displaced longitudinally of 50
- 50 said films, substantially as described. 55
- 55 In testimony whereof we affix our signatures, in presence of two witnesses.
